UNITED STATES PATENT OFFICE

132,358

DESIGN FOR A STIRRUP FOR PHYSICIAN'S EXAMINING TABLE

George E. Froelich, Two Rivers, Wis., assignor to Hamilton Manufacturing Company, Two Rivers, Wis., a corporation of Wisconsin

Application October 2, 1941, Serial No. 103,610

Term of patent 14 years

To all whom it may concern:

Be it known that I, George E. Froelich, a citizen of the United States, residing in Two Rivers, Manitowoc County, Wisconsin, have invented a new, original, and ornamental Design for Stirrup for Physician's Examining Table, of which the following is a specification, reference being had to the accompanying drawing, forming a part thereof.

Figure 1 is a top plan view of a stirrup for physician's examining table, showing my new design;

Figure 2 is a side elevational view thereof; and Figure 3 is a front elevational view thereof.

The characteristic features of the stirrup design illustrated reside in the cross-piece and upper corrugated member having the configuration shown.

I claim:

The ornamental design for a stirrup for physician's examining table, substantially as shown and described.

GEORGE E. FROELICH.
